**DISPENSER FOR PRESSURE-SENSITIVE TAPE
HAVING A SEVERING BLADE ARRANGED
TO BE MOVED AWAY FROM ITS OPERATIVE
POSITION**

Alfred P. Krueger, Stratford, Conn., assignor to Derby Sealers, Incorporated, Derby, Conn., a corporation of Connecticut

Original application September 26, 1951, Serial No. 248,395, now Patent No. 2,647,746, dated August 4, 1953. Divided and this application June 23, 1953, Serial No. 363,442

2 Claims. (Cl. 164—84.5)

This invention relates to tape-dispensing machines and more particularly to a machine for dispensing pressure-sensitive tape or tape which is tacky upon one side, and the present application is a division of my prior application for Dispenser for Pressure-Sensitive Tape, Serial No. 248,395, filed September 26, 1951, now Patent No. 2,647,746.

The present invention relates to a tape-dispensing machine by which the tape is fed from the machine by means of a lever or other manually operated device. This lever is employed to operate a tape-feeding device in the form of a rotatable drum or roll to which the tape is adapted to cling whereby rotation of the feeding member draws the tape from the usual supply roll.

Means are provided for stripping the tape from the feeding device and a severing member is provided adjacent the point of delivery of the tape so that the tape may be drawn against the severing blade and the dispensed portion severed from that remaining upon the supply roll.

As illustrated, the feeding device comprises a pair of spaced elements such as pins extending transversely of the tape and connected to a rotatable support in the form of a disk-like member, the tacky side of the tape clinging to the pins so that when this member is rotated, the feeding operation will be effected. The severing member extends transversely across the path of the tape as it is stripped from the feeding member and the tape issues between the feeding member and the severing blade. As it is desirable to mount the severing blade in relatively close proximity to the tape being fed in order that measured lengths may be accurately dispensed, it is desirable that the severing blade be arranged to be moved away from its operative position so that when a new roll of tape is inserted in the machine the end of the tape may be placed upon the feeding roll in position to be fed without the necessity of its having to be threaded between the feeding member and the severing blade.

One object of the present invention is to provide a new and improved mechanism for dispensing pressure-sensitive tape.

A still further object of the invention is to provide a new and improved means for feeding pressure-sensitive tape consisting of a frame or support upon which may be carried a supply roll of tape, a feeding device, and a severing member, the arrangement being such that the severing member may be moved away from the feeding device to permit the end of a fresh supply of tape to be placed between the severing member and the periphery of the feeding member.

A still further object of the invention is to provide a tape-dispensing mechanism of the character described wherein the severing member is mounted upon a yoke or U-shaped support which is hinged to the frame of the machine so that it may be swung to an inoperative position when desired or moved to an operative position in

which the dispensed tape may be drawn against the severing blade by a user.

A still further object of the invention is to provide a tape-dispensing mechanism having severing means of the character described wherein the support for the severing member is pivoted to the frame of the machine, and spring means are arranged to yieldably hold the severing member either in its operative tape-severing position or in an inoperative position permitting access to the feeding member to place the tape thereon.

To these and other ends the invention consists in the novel features and combinations of parts to be hereinafter described and claimed.

In the accompanying drawings:

Fig. 1 is a side elevational view of a tape-dispensing mechanism embodying my invention;

Fig. 2 is a front elevational view thereof;

Fig. 3 is a partial sectional view on line 3—3 of Fig. 2; and

Fig. 4 is an elevational view of the front part of the machine on the side opposite that shown in Fig. 1.

To illustrate a preferred embodiment of my invention, I have shown in the drawings a tape-dispensing mechanism comprising a frame having a base 10 and spaced upstanding members 11 and 12, these members being secured to the base in any suitable manner, such as by angle brackets 13. Adjacent their rear ends the members 11 and 12 may be provided with supporting lugs 14 and 15, which lugs are provided with grooves 16 to receive and hold the spindles 17 of the spool of the supply roll of tape 18.

Adjacent the forward end of the frame a shaft 19 is rotatably mounted in the plates 11 and 12, and upon this shaft is mounted the actuating crank or lever 20. This shaft 19 is provided with a one-way driving connection with the feeding means which comprises a disk 21 provided with a plurality of spaced transversely extending pins 22 projecting from the disk and secured thereto. The connection between the shaft 19 and the disk 21 may be that described and illustrated in my parent application above referred to.

The tape shown at 23 extends from the supply roll 18, and the tacky surface thereof engages the surface of the spaced pins 22 so that when the disk is rotated the tape will be drawn from the supply roll. The lever 20 is normally urged in a counter-clockwise direction by a spring 24 secured at one end to a pin 25 set in the frame member 12 and secured at its other end to a pin 26 secured to the lever.

In order to strip the tape from the feed elements 22, a stripper is provided which, as illustrated, is in the form of a paddle wheel 28 (Fig. 3). This wheel is rotatably mounted upon a shaft 29 secured in the side frame 12 and comprises a hub 30 from which project a plurality of stripping elements in the form of blades 31. This member is so disposed with relation to the disk 21 and the pins 22 that the blades extend outwardly between the pins so that they engage the tacky side of the tape and strip it from the pins. Also the pins 22 will engage successive ones of the paddles or blades 31 so that the stripping element will be rotated by the rotation of the feed disk 21 and no gears or other driving means are required for driving the stripper.

As described in my prior application above referred to, it is contemplated that the dispenser will be so arranged that it will dispense a measured length of tape upon operation of the handle or lever 20. In order that the dispensed length of tape may be severed, a knife or severing member is provided as shown at 33. This member is secured to the bight portion 34 of a U-shaped support or frame, this frame having legs 35 and 36 which extend downwardly, as shown in Figs. 1 and 3, from the bight

portion of the frame and are pivoted to the frame members 11 and 12, as shown at 37 and 38. The pivots are, of course, coaxial so that the supporting member together with the severing knife 33 carried thereby may be swung from its full-line position, shown in Figs. 3 and 4, to the dotted-line position shown in those figures. A spring 39 secured to a pin 40 on the frame member 11 and to a lug 41 on the leg 36 serves to hold the U-shaped knife-supporting member in either of its two positions of adjustment, and it will be noted, referring to Fig. 4, that the spring 39 is disposed upon one side of the pivot 37 when the support is in its full-line position and disposed on the other side of this pivot when the support is in its dotted-line or inoperative position. Thus the spring passes by the dead center point when the support is moved from one position to the other. A tab 42 may be secured to the bight portion 34 of the U-shaped knife-supporting frame so that this tab may be grasped by the operator and the frame conveniently swung from one position to the other.

Normally the knife support will stand in the position shown in full lines in the drawing, and in this position the knife 33 is in close proximity to the tape 23 as it is stripped from the feed elements 22 by the stripper 28. Thus a measured length of tape may be accurately severed. When, however, it is desired to "load" the machine or place therein a fresh supply of tape, the knife frame may be swung from the full-line position shown in Figs. 3 and 4 to the dotted-line position shown in those figures so that free access is provided to the pins 22 of the feed element in order that the new length of tape may be laid upon and caused to adhere to these pins. So soon as the tape is placed in position the support of the severing member is moved back to its full-line position in which it is in close juxtaposition to the feed elements 22.

The operative position of the knife support is determined by engagement of the severing member 33 with the forward edges of the frame members 10 and 11, while the inoperative position of the support of the severing member is determined by the engagement of the tab 42 with the base plate 10.

While I have shown and described a preferred embodiment of my invention, it will be understood that it is not to be limited to all of the details shown, but is capable of modification and variation within the spirit of the invention and within the scope of the claims.

What I claim is:

1. In a mechanism for dispensing pressure-sensitive tape, a frame having a base and spaced side walls rising

from the base, a feed member rotatably supported by the frame between said walls to deliver tape between the front edges thereof, a severing member, a support for said member, said support being of U-shaped form and comprising a pair of spaced leg members and a bight portion joining the leg members at one end thereof, said severing member being secured to said bight portion and abutting the front edges of the walls of the frame when said severing member is in operative position, each of said leg members being pivoted to one of said side walls whereby the support may swing about a horizontal axis to move the severing member from an upper operative position to a lower inoperative position to permit access to the feed member, and means urging said severing member against the edges of the walls of the frame.

2. In a mechanism for dispensing pressure-sensitive tape, a frame having a base and spaced side walls rising from the base, a feed member rotatably supported by the frame between said walls to deliver tape between the front edges thereof, a severing member, a support for said member, said support being of U-shaped form and comprising a pair of spaced leg members and a bight portion joining the leg members at one end thereof, said severing member being secured to said bight portion and abutting the front edges of the walls of the frame when said severing member is in operative position, each of said leg members being pivoted to one of said side walls whereby the support may swing about a horizontal axis to move the severing member from an upper operative position to a lower inoperative position to permit access to the feed member, a spring secured at one end to one of said leg members and at the other end to the frame in such position that said spring passes a dead-center position in the movement of the support from an operative to an inoperative position, and means on said U-shaped support engaging the base to limit movement of the support to an inoperative position.
